TRANSVERSE ROAD JOINT

Robert R. Robertson, Chicago, Ill., assignor to
 The Translode Joint Company, Chicago
 Heights, Ill., a corporation of Illinois

Application May 24, 1937, Serial No. 144,423

12 Claims. (Cl. 94—18)

This invention relates to transverse road joints adapted to be positioned transversely of a road between the center joint and the outer side of the road for the purpose of connecting adjacent road slabs for the transmission of loads from one road slab to another, said transverse joints arranged to be anchored in the adjacent road slabs with the intermediate portion of each joint looped in opposite directions with the looped portions separated by a middle section which is not anchored to either of the road slabs and which is covered to prevent bonding to the concrete forming the road slabs between which the joint is embedded.

It is an object of this invention to provide a road transverse joint comprising upper, lower and intermediate plate sections which are connected together by means of bight portions which project in opposite directions for embedding in adjacent concrete road slabs between which the joint is disposed, each of said upper and lower plate sections having a covering on one side thereof, with said covering extending to cover part of the intermediate plate section to obviate bonding of the concrete with the side surfaces of the intermediate plate section.

It is an object of this invention to provide an improved type of transverse road joint comprising upper, lower and middle plate sections disposed in substantially the same plane and integrally connected by means of spring-like looped anchoring sections which project in opposite directions from opposite sides of the joint and are separated by the middle plate section.

It is a further object of this invention to provide an improved type of transverse road joint comprising upper, lower and middle plate sections connected by oppositely projecting looped portions, said looped portions having engaged thereto in reinforcing members, portions of which project to be disposed on opposite sides of the middle plate section to reinforce the middle portion of the joint.

It is furthermore an object of this invention to provide a transverse road joint wherein upper, lower and intermediate plate sections are integrally connected by means of looped portions projecting in opposite directions and separated by the middle plate section and by a reinforcing bar or filler member disposed adjacent one side of the intermediate plate section to provide an increased thickness of material at the middle portion of the joint throughout the entire length of the joint.

Another object of the invention is the provi-

sion of a transverse road joint wherein reversed diagonally opposite angle sections are connected by an intermediate Z-shaped section, which, if desired, may be strengthened by means of reinforcing members positioned to increase the thickness of material at the middle portion of the joint.

Still another object of the invention is the provision of a road joint comprising reversed diagonally opposite angle sections integrally connected by means of a Z-shaped intermediate section, said angle sections being provided with anchoring members whereby the angle sections are anchored to opposite road slabs, said joint also including diagonally opposite pads or coverings which separate each of the angle sections from the road slabs opposite the road slabs in which the angle sections are anchored.

It is an important object of this invention to provide a transverse road joint adapted to be supported in position before the pouring of concrete by means of supporting shoes, said joint comprising upper and lower plate sections having both horizontal and vertical anchoring members struck therefrom, said upper and lower plate sections being integrally connected by means of an intermediate plate section and oppositely projecting looped portions which respectively project in the direction of the anchoring members, said joint adapted to be strengthened, if desired, with reinforcing means for the intermediate plate section and with coverings on diagonally opposite sides of the joint to prevent bonding of concrete with the covered sides of the joint to permit the upper and lower plate sections of the joint, to be moved in opposite directions from one another, with the contraction and the expansion of the concrete road slabs due to temperature changes or other causes.

Other and further important objects of this invention will be apparent from the disclosures in the specification and the accompanying drawings.

The invention (in preferred forms) is illustrated in the drawings and hereinafter more fully described.

On the drawings:

Figure 1 is a fragmentary top plan view of a transverse road joint forming mechanism embodying the principles of this invention, with the concrete omitted and showing supporting shoes for holding the joint forming mechanism in position upon a road subgrade prior to the pouring of concrete.

Figure 2 is a fragmentary side elevation of the

joint forming mechanism illustrated in Figure 1.

Figure 3 is an enlarged fragmentary vertical detail section through the transverse joint shown embedded between concrete road slabs.

- 5 5. Figure 4 is a fragmentary isometric view of a modified form of transverse joint forming mechanism engaged in supporting shoe and including reinforcing members for the middle portion of the joint.
- 10 10. Figure 5 is a fragmentary isometric view of another modified form of transverse road joint, and one of the supporting shoes therefor and illustrating a modified form of reinforcing means for the middle portion of the joint.
- 15 15. As shown on the drawings:
- The improved transverse road joint illustrated in Figures 1, 2, and 3, is adapted to be supported upon a road subgrade 1 by means of a plurality of spaced supporting shoes each of which comprises a middle channel section 2 having inverted U-shaped side walls 3 to which supporting flanges 4 are integrally connected. The shoe supporting flanges 4 are provided with openings or apertures 5 for the reception of retaining stakes 6 which are driven into the subgrade 1 as illustrated in Figure 3.
- 20 20. As clearly illustrated in Figure 3, the joint forming mechanism after being secured in a selected position upon the road subgrade is embedded in concrete, which forms the road slabs 7 and 8 on opposite sides of the joint.
- 25 25. The joint forming mechanism is constructed of sheet metal which is bent or formed to provide a top plate 9, a bottom plate 10 and an intermediate plate 11, all of which are disposed in substantially the same plane. The lower margin of the top plate 9 is bent outwardly at substantial right angles to provide a flange plate 12, which together with the plate 9 form an upper angle section. The upper margin of the lower plate 10 is deflected outwardly to form a flange plate 13 which coacting with the bottom plate 10 forms a lower angle section which is positioned diagonally opposite and in an inverted position with respect to the upper angle section 9-12. The upper margin of the intermediate plate 11 is deflected outwardly and forms a flange plate 14 while the lower margin of the intermediate plate 11 is deflected outwardly, in an opposite direction, to 30 30. form a lower flange plate 15. The intermediate plate 11 together with the upper and lower flanges 14 and 15 thereof form a middle Z-section with the upper flange plate 14 positioned adjacent the flange plate 12 while the lower flange plate 15 of the intermediate section is positioned adjacent the flange plate 13. Integrally connecting the flange plates 12 and 14 is a bight or sleeve 16. The flange plates 13 and 15 are integrally connected by means of a bight or sleeve 17. The flange plates 12 and 14 connected by means of the sleeve 16 forms a looped anchoring section which projects in a direction opposite from a looped anchoring section formed by the plates 13 and 15 and the sleeve 17. The two anchoring loops project in opposite directions and are positioned at different elevations separated by the intermediate plate 11 which forms a part of the main body of the joint. The looped anchoring section, formed by the plates 12 and 14 and the sleeve portion 16, is embedded in the road slab 7, while the lower anchoring looped section formed, by the plates 13 and 15 which are connected by the sleeve 17, is embedded in the opposite road slab 8. Struck outwardly from one side of the joint top plate 9 are vertical anchoring wings or blades 18,

and horizontal anchoring wings or blades 19. Struck outwardly from the lower joint plate 10, for embedding in the road slab 8, are vertical anchoring wings or blades 20 and horizontal anchoring wings or blades 21. The upper and lower groups of anchoring wings or blades project from opposite sides of the joint above and below the intermediate section of the joint forming an arrangement whereby the upper portion of the joint is anchored in one road slab, while the lower portion of the joint, is anchored in the opposite road slab. Anchoring of the looped portions of the joint, in the opposite road slabs 7 and 8 serves to connect the opposite slabs through the middle or intermediate plate 14 of the joint.

15 Positioned adjacent a side, of the joint top plate 9, opposite the anchoring rings or blades is a cushion or pad 22 constructed of asphalted roofing felt or other suitable material which extends downwardly to cover the opening between the flange plates 12 and 14 and continues on to cover one side of the intermediate plate 11 down to the flange plate 15, thereby providing an arrangement preventing bonding of the concrete of the road slab 8 with the top plate 9 and the intermediate or middle plate 11 of the joint. Positioned on the diagonally opposite side of the joint mechanism, as clearly illustrated in Figure 3 is a lower cushion or pad 23, also constructed of asphalted roofing felt or other suitable material and covering the plain side of the lower joint plate 10 and the opposite side of the intermediate or middle plate 11 of the joint.

20 The lower cushioning pad 23 also extends across the opening between the flange plates 13 and 15 of the lower looped section and extends upwardly to contact the flange plate 14 thereby affording a construction preventing bonding of the concrete, forming part of the road slab 7, with the lower joint plate 10 and with the intermediate or middle joint plate 11. By referring to Figure 3, it will be noted that the pads or coverings 22 and 23 are positioned on diagonally opposite sides of the joint, and cover both sides of the intermediate or middle plate 11, and the sides of the upper and lower plates 9 and 10, opposite from the sides from which the anchoring blades project.

25 25. Figure 4 illustrates a modified form of transverse road joint which normally is adapted to be supported in position upon a road subgrade by means of channel shaped supporting shoes similar to those used in the joint construction illustrated in Figures 1 to 3 inclusive.

The modified form of transverse road joint is formed out of sheet steel or other suitable material and comprises a top plate 24, a bottom plate 25 and a middle or intermediate plate 26, all of which are positioned in substantially the same plane. Integrally formed at substantially right angles to the lower margin of the top plate 24 is a flange plate 27, which together with the top plate 24 forms a top angle section. Integrally formed on the upper margin of the bottom plate 26, is a flange plate 28, which together with the bottom plate 26 forms a lower angle section which is inverted and diagonally opposite to the upper angle section. Integrally formed at substantially right angles to the upper margin of the intermediate plate 25 is a flange plate 29 which is integrally connected with the flange plate 27 by a bight portion 30. Integrally formed at substantially right angles on the lower margin of the intermediate plate 25, is a flange plate 31, which is integrally connected with the lower

contraction and expansion of the road slabs due to temperature changes.

It will of course be understood that various details of construction may be varied through a wide range without departing from the principles of this invention, and it is therefore, not the purpose to limit the patent granted thereon, otherwise than necessitated by the scope of the appended claims.

10 I claim as my invention:

1. In a transverse joint for embedding between adjacent concrete road slabs, a joint forming mechanism comprising an upper plate including anchoring members projecting from one side thereof, a lower plate including anchoring members projecting from one side thereof, an intermediate plate disposed between the upper plate and the lower plate and substantially in the plane of one of said plates, looped anchoring sections projecting from opposite sides of the joint forming mechanism and integrally connecting the upper plate and said lower plate with the intermediate plate, and coverings of compressible material disposed on diagonally opposite sides of the joint forming mechanism to cover one side of the upper plate and one side of the lower plate, and both sides of the intermediate portion of the joint to obviate the adherence of said intermediate portion of the joint to said road slabs.

2. In a transverse joint for embedding between adjacent concrete road slabs, said joint comprising upper and lower angle sections reversed and disposed diagonally opposite one another, an intermediate Z-section between the angle sections, eight portions integrally connecting the intermediate Z-section with the upper and lower angle sections, anchoring members struck from one side of each of said upper and lower angle members and leaving openings therein, and compressible coverings on the opposite side of each of said upper and lower angle members and covering the openings therein.

3. A transverse joint forming mechanism for embedding between concrete road slabs, said mechanism comprising reversed diagonally opposite angle sections, an intermediate Z-shaped section separating the angle sections, anchoring loops integrally connecting the angle sections with the intermediate Z-shaped section, anchoring members formed on said angle sections with the anchoring members of one angle section embedded in one of the concrete road slabs while the anchoring members of the other angle section are embedded in the opposite road slab, and a covering on each of said angle members, said coverings positioned on diagonally opposite sides of the joint forming mechanism and extending to cover both sides of the middle portion of the intermediate Z-shaped section of the joint.

4. A transverse joint for embedding between adjacent concrete road slabs, said joint comprising upper and lower plates having anchoring means formed thereon, an intermediate plate disposed in substantially the plane of said upper and lower plates, looped portions projecting in opposite directions and integrally connecting the upper and lower plates with said intermediate plate, reinforcing means adjacent the intermediate plate to increase the thickness of the material at the middle portion of the joint, and coverings for said upper and lower plates positioned on diagonally opposite sides of the joint and extending to cover one side of the intermediate plate and one side of the reinforcing means.

5. A transverse joint forming mechanism for

embedding between adjacent concrete road slabs and comprising upper and lower plates, an intermediate plate disposed in substantially the same plane as said upper and lower plates, looped sections integrally connecting the upper and lower plates with said intermediate plate and projecting from opposite sides of the joint forming mechanism, and reinforcing members engaged in the looped portions and covering opposite sides of the intermediate plate.

6. A transverse joint forming mechanism for embedding between adjacent concrete road slabs and comprising upper and lower plates, an intermediate plate disposed in substantially the same plane as said upper and lower plates, looped sections integrally connecting the upper and lower plates with said intermediate plate and projecting from opposite sides of the joint forming mechanism, reinforcing members engaged in the looped portions and covering opposite sides of the intermediate plate, and anchoring members formed on said upper and lower plates with the anchoring members of one of said plates projecting in a direction opposite from the direction of projection of the anchoring members from the other of said plates.

7. A transverse joint forming mechanism for embedding between adjacent concrete road slabs and comprising upper and lower plates, an intermediate plate disposed in substantially the same plane as said upper and lower plates, looped sections integrally connecting the upper and lower plates with said intermediate plate and projecting from opposite sides of the joint forming mechanism, reinforcing members engaged in the looped portions and covering opposite sides of the intermediate plate, anchoring members formed on said upper and lower plates with the anchoring members of one of said plates projecting in a direction opposite from the direction of projection of the anchoring members on the other of said plates, and a covering on one side of each of said upper and lower plates extending to the looped portion on the respective side of the joint forming mechanism to cover the reinforcing means on that side of the intermediate portion of the joint forming mechanism.

8. A road joint forming mechanism for embedding between adjacent concrete road slabs and comprising upper and lower plates having anchoring members projecting from one side thereof, an intermediate plate between said plates and parallel thereto, looped portions integrally connecting the upper and lower plates with said intermediate plate and opening in opposite directions, reinforcing members engaged in the looped portions and projecting therefrom to cover the opposite sides of the intermediate plate, and coverings on one side of the upper and lower plates and projecting to the looped portions of the joint to cover opposite sides of the reinforced intermediate portion of the joint.

9. A transverse road joint forming mechanism for embedding between adjacent concrete road slabs, said joint forming mechanism comprising upper and lower plates having anchoring members projecting therefrom, an intermediate plate between said plates, oppositely projecting, looped portions integrally connecting the upper and lower plates with the intermediate plate, and a reinforcing block between the looped portions and adjacent one side of the intermediate plate to increase the thickness of the material at the middle portion of the joint between the looped portions.

flange plate 28, by means of a bight portion 32. The intermediate plate 25 with the upper and lower flanges 29 and 31 forms an intermediate Z-shaped section which integrally connects the upper and lower angle sections of the joint. The upper flange plates 27 and 29, connected by the bight portion 30, forms a looped section which projects outwardly from one side of the joint, while the lower flange plates 28 and 31, connected by the bight portion 32, form a lower looped section which projects outwardly from the opposite side of the joint and is spaced below the upper looped section by the intermediate flange plate 25.

15 Struck outwardly from the upper and lower plates 24 and 26 are horizontal anchoring wings or blades 33 and vertical anchoring wings or blades 34. The anchoring blades 33 and 34 are staggered with respect to one another. The upper anchoring wings or blades 33 and 34, which are struck outwardly from the top plate 24, project over the flange plate 27, while the lower anchoring wings or blades 33 and 34, struck from the lower joint plate 26, project in an opposite direction beneath the flange 28.

20 For the purpose of reinforcing the intermediate portion of the joint forming mechanism, metal reinforcing angles 35 are mounted in reverse staggered relation with one of the flanges of the upper angle iron 35 projecting into the upper looped portion between the flange plates 27 and 29 while the other flange of the angle iron is positioned adjacent one side of the intermediate plate 25. The lower reinforcing angle iron 35 is positioned with one of the flanges thereof projecting between the flange plates 28 and 31 of the lower looped portion, while the other flange of the lower angle iron is positioned adjacent the opposite side of the intermediate plate 25. It will thus be seen that the middle plate 25 of the joint is reinforced by the flanges of the angle iron positioned on opposite sides thereof to form an increased thickness of metal at the middle portion of the joint.

25 Secured to the side of the upper plate 24, opposite the side from which the anchoring blades project, is an upper covering or pad 36 constructed of asphalted roofing felt or other suitable material. The covering 36 extends downwardly and covers the outer side of the downwardly projecting flange of the top angle member 35, with the lower edge of the pad 36 resting upon the flange 31. Secured on the side of the lower plate 26, opposite the anchoring blades, is a lower covering or pad 37 constructed of asphalted roofing felt or other suitable material. The covering or pad 37 extends upwardly to cover the outer face of the upwardly projecting flange of the lower reinforcing angle iron 35. The covering or pad 37 extends upwardly until the upper edge contacts the flange 29. The covers or pads 36 and 37 act to prevent bonding of concrete with the plain sides of the upper plate 24 and the lower plate 26, and with the exposed surfaces of the reinforcing angle members 35.

30 Figure 5 illustrates another modified form of transverse road joint, which is adapted to be mounted in position on a road subgrade by means of channel shaped anchoring shoes similar to those used with the joint illustrated in Figures 1 to 3 of the drawings. In this modified form of the transverse joint, the members are constructed out of sheet steel or other suitable material and comprise a top plate 38, a bottom plate 39 and an intermediate plate 40, said lower plate 39 and

the intermediate plate 40 being disposed in substantially the same plane while the upper plate 38 is placed to one side thereof. Integrally formed on the lower margin of the top plate 38 is a flange plate 41 which together with the plate 38 form an upper angle section. Integrally formed on the upper edge of the middle or intermediate plate 40 is a flange plate 42 which is positioned to contact the bottom surface of the flange plate 41. Integrally connecting the flange plates 41 and 42 is an anchoring sleeve or tube 43 which together with the flange plates 41 and 42 forms an upper looped anchoring section. Integrally formed on the upper margin of the lower joint plate 39 is a flange plate 44, which is positioned in contacting relation, with a flange 45, which is integrally formed on the lower margin of the intermediate or middle plate 40. Integrally connecting the flange plates 44 and 45 is a lower anchoring tube or sleeve 46 which together with the flange plates 44 and 45 form a lower looped anchoring section which projects in a direction opposite from the upper looped section. The two looped sections are connected by the middle section which is of Z-shape comprising the middle plate 40 with the flanges 42 and 44. Horizontal anchoring wings or blades 47 are struck outwardly from one side of both the upper and lower plates 38 and 39. Each of said plates also has struck therefrom vertical anchoring wings or blades 48 which are staggered with respect to the blades or wings 47. The upper anchoring blades or wings 47 and 48 project outwardly over the upper looped anchoring section while the lower anchoring wings or blades 47 and 48 project outwardly beneath the lower looped anchoring section.

35 For the purpose of reinforcing the middle portion of the joint, a metal reinforcing block or bar 49 is positioned adjacent one side of the intermediate or middle plate 40 and between the flanges 41 and 45 to fill the space beneath the projecting portion of the flange plate 41 between the upper plate 38 and the intermediate plate 40 thereby providing an intermediate portion of the joint of increased thickness.

40 Secured to one side of the top joint plate 38, opposite the side from which the anchoring blades project, is an upper cover or pad 50 constructed of asphalted roofing felt or other suitable material. The pad or cover 50 extends downwardly to the flange 45 and covers the outer exposed surface of the reinforcing block or bar 49. Secured to the plain side of the lower plate 39, is a lower covering or pad 51, which is also constructed of asphalted roofing felt or other suitable material. The lower pad 51 extends upwardly to the flange 42 and covers one surface of the middle or intermediate joint plate 40.

45 The pads 50 and 51 obviate bonding of the concrete with diagonally opposite sides of the joint mechanism. With the improved joint forming mechanism mounted in position as illustrated in Figure 5, upon a road subgrade, transversely of the road, concrete is poured on opposite sides of the joint forming mechanism to form road slabs. The lower portion of one side of the joint forming mechanism is anchored to one of the road slabs while the upper portion on the opposite side of the joint is anchored in the adjacent road slab. A transverse joint is thus provided, between the road slabs, whereby loads are adapted to be transmitted from one road slab to another through the intermediate portion of the joint. The joint is also formed to compensate for the

10. A road joint forming mechanism comprising in combination a supporting means, upper and lower plates having anchoring means formed thereon with said lower plate engaged in the supporting means, an intermediate plate disposed in the plane of said lower plate and to one side of the plane of said upper plate, upper and lower looped portions projecting in opposite direction and integrally connecting the upper and lower plates with said intermediate plate, and a reinforcing bar engaged between the looped portions and adjacent one side of the intermediate plate.
11. A road joint forming mechanism including in combination a supporting means, upper and lower plates with said lower plate engaged in the supporting means, an intermediate plate, looped portions integrally connecting the upper and lower plates with said intermediate plate and projecting from opposite sides of the joint at different elevations separated by the intermediate plate, and reverse reinforcing angle mem-
- bers disposed adjacent opposite sides of the intermediate plate and projecting into the looped portions of the joint.
12. A road joint forming mechanism for embedding between concrete slabs and comprising upper and lower plates, an intermediate plate separating the same and disposed in a plane parallel to said upper and lower plate, looped portions projecting in opposite directions from one another and disposed at different elevations and integrally connecting the upper and lower plates with said intermediate plate, and covering means on opposite sides of the intermediate plate and covering one side of each of said upper and lower plates and the open sides, of the looped portions of the joint to prevent the entrance of concrete into said looped portions and preventing the adherence of said intermediate plate to either of the concrete slabs.

ROBERT R. ROBERTSON. 20
